SURGICAL KNIFE

Joseph Navara, 2105 W. Walton St.,
Chicago, Ill. 60622

Filed Jan. 7, 1971, Ser. No. 104,844

Term of patent 14 years

Int. Cl. D24—02

U.S. Cl. D83—12 R

FIG. 4

FIG. 2

FIG. 1

FIG. 3

FIG. 5

FIG. 1 is a side elevational view of a surgical knife showing my new design, the side opposite being a mirror image thereof;

FIG. 2 is a top plan view thereof.

FIG. 3 is a bottom plan view thereof.

FIG. 4 is an end view thereof as seen from the handle end; and

FIG. 5 an end view thereof as seen from the blade end.

I claim:

The ornamental design for a surgical knife, as shown and described.
